ATTORNEY

UNITED STATES PATENT OFFICE.

GEORGE FLEMING, OF PRINCETON, TEXAS.

SHOTGUN.

1,266,573.

Specification of Letters Patent. Patented May 21, 1918.

Application filed January 18, 1917. Serial No. 143,124.

To all whom it may concern:

Be it known that I, GEORGE FLEMING, a citizen of the United States, residing at Princeton, in the county of Collin and State 5 of Texas, have invented certain new and useful Improvements in Shotguns, of which the following is a specification.

This invention relates to shot guns and primarily contemplates using an electrical 10 source of energy for impelling a shot.

Another object of the invention is to provide a trigger operated gun which closes an electrical circuit, immediately upon contact with the shell, to create a spark for igniting a combustible fluid or material, 15 through the medium of which the shot is projected.

Other objects as well as the nature, characteristic features and scope of my invention will be more readily understood from 20 the following description taken in connection with the accompanying drawings and pointed out in the claims forming a part of this specification.

25 In the drawings:

Figure 1 is a longitudinal sectional view of a gun constructed in accordance with my invention.

Fig. 2 is a detail fragmentary longitudinal sectional view of the device, and

Fig. 3 is a perspective view of the trigger mechanism used in this invention.

In the drawings, a gun stock 1 is provided, which has a barrel 2 pivotally associated therewith in the usual or any desired manner.

The stock 1 is provided with a longitudinally extending recess in which an electrical source of energy 3 is mounted, which in this 40 instance consists of a pair of dry cells. The recess is accessible through a door 4 hinged on the free terminal of the gun stock. A pair of circuit wires 5 extend from the battery and terminate in a chamber 6 formed in said stock. A plate 7 is mounted upon the forward end of the stock 1, and has one end thereof bent at right angles, as indicated at 8, to snugly engage the inner terminal of the barrel 2 when the latter is in 45 an operative position. The plate is provided in its right-angled end with an opening 9, and is furthermore provided in its body with an opening 10, in which a suitable insulating ring 11 is mounted. The

50 rear end of the plate 7 is grounded to one

of the circuit wires 5, as illustrated to advantage in Fig. 2.

A trigger 12 is pivotally mounted in the stock, and has one end thereof projected through the opening 10. The terminal of 60 said end is bent at an angle, as indicated at 13, and constitutes a contact for one side of the circuit. The lower end of the trigger, as indicated at 14, is formed to provide a finger piece for operating the trigger and 65 is made of any suitable insulating material.

An arm 15 is pivotally mounted upon the shank of the trigger 12 and is equipped with a contact plate 16 to which the other circuit wire 5 is grounded. It will be noted 70 that the contact plate 16 is mounted in the chamber 6 so as to move freely therein upon operation of the trigger 12.

A shell 17 is mounted in the bore of the barrel 2. The shell is adapted to contain 75 powder, gas or any other suitable combustible fluid or material which when ignited will impel or project a bullet therefrom. The shell has a spark plug 18 mounted therein, whereby contact of the end 13 of the trigger with said spark plug will close the electrical circuit, and cause the contents of said shell 17 to be ignited. In order to normally hold the trigger out of engagement with the spark plug a spring 19 is provided, one end 85 of which is engaged with the arm 15 and the opposite end engaged with a portion of the stock 1.

From the above it will be obvious that when pressure is exerted on the trigger 12, 90 the contact end 13 thereof will move through the opening 9 and into contact with the spark plug of the shell 17. The shell 17 is, of course, in contact with the plate 8, so that the circuit will be completed through the 95 trigger 12 and plate 8 with an obvious result.

It will be understood that the above description and accompanying drawings comprehend only the general and preferred embodiment of my invention and that various minor changes in details of construction, proportion and arrangement of parts may be made within the scope of the appended claims and without sacrificing any of the 105 advantages of my invention.

I claim:

1. In a shot gun, a stock, a barrel mounted thereon, a plate mounted on said stock and having its forward end turned up sub- 110

stantially at right angles to provide a closure member for the inner end of the barrel, a source of electrical energy mounted in said stock, one side of said source of electrical energy being connected to said plate, and a trigger mounted in the stock and operative through the plate, said trigger being provided at its upper end with an angularly disposed contact member adapted 10 to extend through the forward up-turned end of the plate when the trigger is moved into operative position, said trigger being electrically connected to the other side of said source of electrical energy.

15. 2. In a shot gun, a stock, a barrel carried thereby, a plate mounted on the stock and having its forward end turned up substantially at right angles to provide a breech block for closing the barrel when in operative position, a source of electrical energy mounted in said stock, one side of said source being connected to said plate, a trigger mounted in the stock and operative through the plate, said trigger being pro-

vided at its upper end with an angularly disposed contact member adapted to extend through the forward upturned end of the plate when the trigger is moved into operative position, and means for normally holding said trigger in inoperative position and for connecting the trigger to the other side of said source of electrical energy.

3. A shot gun including a stock equipped with a source of electrical energy, a trigger mounted in said stock, an arm floatingly mounted in said stock having one end pivotally secured to the trigger and the opposite end enlarged to form a contact to place said trigger in circuit with said electrical energy, and a barrel mounted on said stock and in circuit with said electrical energy substantially as set forth.

In testimony whereof, I affix my signature in presence of two witnesses.

GEORGE FLEMING.
